UNITED STATES PATENT OFFICE.

EUNICE KIEL WILSON, OF LOS ANGELES, CALIFORNIA.

SLEEVE.

1,262,891.

Specification of Letters Patent. Patented Apr. 16, 1918.

Application filed June 28, 1917. Serial No. 177,426.

To all whom it may concern:

Be it known that I, EUNICE KIEL WILSON, a citizen of the United States, residing at Los Angeles, in the county of Los Angeles 5 and State of California, have invented a new and useful Sleeve, of which the following is a specification.

This invention relates to the sleeves of garments, for example the sleeves of dresses, 10 shirts and blouses, and an object of the invention is to make provision for shortening a sleeve in such manner that it will have the appearance of a half length sleeve.

Sleeves of this character are useful for the 15 reason that when the person desires an ordinary full length sleeve such sleeve can be readily provided, and if the person desires to shorten the sleeve so as to make it more comfortable for work or sport said sleeve 20 can be readily adjusted to the shorter length and will in its shortened condition present a neat appearance.

Another object is to produce a sleeve of this character of comparatively simple construction.

Other objects and advantages will appear in the subjoined detail description.

The accompanying drawings illustrate the invention.

30 Figure 1 is a full length view of a sleeve constructed in accordance with this invention, a fragment of the body of the garment to which the sleeve is attached also being shown.

35 Fig. 2 is a view of the sleeve shown in Fig. 1 folded to reduce the length thereof.

Fig. 3 is an enlarged sectional elevation on line indicated by x^3-x^8 , Fig. 1.

40 Fig. 4 is an enlarged sectional elevation on line indicated by x^4-x^4 , Fig. 2.

Fig. 5 is an enlarged plan section on line indicated by x^5-x^5 , Fig. 2.

45 There is provided a tubular member 1 of the usual or any preferred shape and size to constitute the main member of the sleeve. The outer end of the tubular member 1 may be provided with a band 2 to form a finishing strip or trimming.

50 nearer the outer end of the tubular member 1 than the inner end there is fastened by stitching 3 to said tubular member a supplemental cuff or trimming 4, the stitching being at the inner edge of said cuff. In the instance shown, see Fig. 1, the stitching 3 is 55 located substantially one-third of the length of the sleeve from the outer end thereof.

When the tubular member 1 is extended as in Fig. 1 the cuff 4 is adapted to lie within the tubular member so that there are two thicknesses of material at the portion of the 60 sleeve containing the supplemental cuff 4. The outer edge of the cuff 4 may also be fastened to the tubular member by suitable stitching but it is preferred to allow said outer edge to be free from the tubular member 65 for a reason which will appear hereinafter.

Between the outer edge of the cuff 4 and outer end of the tubular member, when the sleeve is extended as in Fig. 1, there is fastened by stitching 5 to the usual cuff portion 6 of the sleeve one end of a strap 7, there being suitable means to detachably fasten the otherwise free end of the strap to the cuff 6. In the instance shown in the drawings the fastening means comprise a button-hole 8 in the strap 7 and a button 9 fastened to the cuff 6, but it is understood that any other well known or preferred fastening means may be employed in this connection. 80 The length of the strap and the position of the button 9 are such that the cuff 6 is contracted or reduced in diameter when the strap is fastened to the cuff 6 by the button 9. Thus the cuff 6 will fit around the wrist 85 of the person wearing the garment having the sleeve attached thereto, and said sleeve will function in the ordinary manner of a full length sleeve without any tendency for the cuff of the sleeve to slide up the arm if 90 the arm be raised. It will be clear from the foregoing that when it is desired to have a full length sleeve the parts will be disposed as shown in Fig. 1 of the drawings.

When for any reason it is desired to 95 shorten the sleeve, the strap 7 will first be unbuttoned so as to allow the cuff 6 to expand to its full diameter and then said cuff 6 will be folded backward on the outside of the portion 10 of the tubular member overlying 100 the supplemental cuff 4 so as to form the fold α , Fig. 4, and finally the cuff 6 and the overlying portion 10 will together be folded back upon the portion 11 of the tubular member lying just above the stitching 3 so 105 as to form the fold β , Fig. 4. This last folding operation brings the supplemental cuff 4 in position on the outside of the sleeve so as to overlie the cuff 6 and portions 10 and 11 as clearly shown in Fig. 4. It is clear 110 that owing to the one edge of the cuff 4 being free as hereinbefore noted, from the

tubular member 1 the cuff 4 can be made to extend above the fold α so as to entirely hide from view the cuff 6 and portion 10, as clearly shown in Fig. 4. It is also clear that if the cuff 6 is comparatively wide it may be necessary when making the second folding operation to produce a third fold α as in Fig. 4 in order that the fold α will be hidden by the cuff 4. Thus it is clear that when the folding operations are completed the cuff 6 and portion 10 will lie between the cuff 4 and the portion 11 of the tubular member 1 as in Fig. 4 so that there will be at least four thicknesses of material at the outer end of the sleeve.

I reserve the right to make such alterations and changes in the specific construction described above as fall within the spirit and scope of the invention as defined in the appended claims.

Of course the cuff 6 may be otherwise constructed than described and shown without limiting the invention.

I claim:

1. A sleeve comprising a tubular member, and a supplemental cuff fastened to the tubular member and adapted to lie therewithin and spaced from the adjacent end of the tubular member when said tubular member is extended and adapted to overlie the folds in the tubular member when said member is folded back upon itself to shorten it, the upper end of the cuff when the sleeve is folded being free from the tubular member.

2. A sleeve comprising a tubular member, a supplemental cuff fastened to the tubular member and adapted to lie therewithin

when said tubular member is extended and adapted to overlie the folds in the tubular member when said member is folded back upon itself to shorten it, a strap fastened at one end to the outside of the sleeve, and means to detachably fasten the other end of the strap to the sleeve to reduce the diameter thereof below the supplemental cuff when the tubular member is extended.

3. A sleeve comprising a tubular member, and a supplemental cuff fastened to the tubular member and adapted to lie therewithin and spaced from the adjacent end of the tubular member when said tubular member is extended and adapted to form an external trimming to the sleeve when the tubular member is folded back upon itself between the cuff and other unfolded portions of the tubular member, the upper end of the cuff when the sleeve is folded being free from the tubular member.

4. A sleeve having a supplemental trimming between the ends thereof adapted to lie within the sleeve and spaced from the adjacent end of the sleeve when said sleeve is at full length and adapted when the sleeve is folded back upon itself to overlie the folded portions, and means to reduce the diameter of the sleeve below the supplemental trimming when the sleeve is extended.

Signed at Los Angeles, California, this 20th day of June, 1917.

EUNICE KIEL WILSON.
